[57] CLAIM

The ornamental design for a fixture for heating and ventilating devices including a louvered flap ventilator arrangement for selectively directing and controlling air flow, as shown and described.

DESCRIPTION

FIG. 1 is a perspective view showing my design of a fixture for heating and ventilating devices including a louvered flap ventilator arrangement for selectively directing and controlling air flow in the closed position;
FIG. 2 is a top view thereof;
FIG. 3 is a front view thereof;
FIG. 4 is a bottom view thereof;
FIG. 5 is a side view thereof;
FIG. 6 is a side view thereof in a partly open position;
and
FIG. 7 is a perspective view thereof in an open position.

FIG. 1

FIG. 2

FIG. 3

FIG. 4

FIG. 6

FIG. 5

FIG. 7
